United States Patent Office.

GEORGE JOSEPH BYRNE, OF NEW YORK, N. Y.

Design No. 3,848, dated February 15, 1870.

DESIGN FOR BOTTLE.

The Schedule referred to in these Letters Patent and making part of the same.

I, GEORGE JOSEPH BYRNE, of New York, in the county and State of New York, have invented and produced a new and original Design for a Bottle, intended to be used by me in bottling the great American genuine Florida water.

The nature of my design is fully represented in the two accompanying photographic illustrations, numbers one and two, to which reference is made.

I claim as my invention—
The design for a bottle, as shown.

GEORGE J. BYRNE.
